UNITED STATES PATENT OFFICE.

CARL A. PALMGREN, OF CHICAGO, ILLINOIS.

RELAY DEVICE FOR ELECTRIC CIRCUITS.

No. 919,066.

Specification of Letters Patent. Patented April 20, 1909.

Application filed April 18, 1907. Serial No. 368,996.

To all whom it may concern:

Be it known that I, CARL A. PALMGREN, of Chicago, Cook county, Illinois, have invented a new and useful Relay Device for Electric Circuits, of which the following is a full, clear, and exact description, reference being had to the accompanying drawings, forming part of this specification, in which—

Figure 1 is a front elevation of a relay device embodying my invention; and Fig. 2 is a section on the line II—II of Fig. 1.

My invention has relation to the class of relays, and is designed to provide a relay device which is particularly adapted for use where the circuit controlled thereby is required to carry a comparatively heavy current, my object being to provide a relay having its circuit controlling contacts so arranged as to be separated in such a manner when the circuit is open as to prevent the maintenance of arcs between the contacts.

With this object in view, my invention consists in the novel construction, arrangement and combination of parts, all substantially as hereinafter described.

Referring to the accompanying drawings, 2 designates the coils of the relay magnets which are connected in the local circuit 3 in the usual manner, and which are provided with the pole pieces 4.

5 designates an armature which is carried by the short arm of a lever 6 pivoted at 7 in a suitable supporting bracket 8. The 35 longer arm of this lever carries at its free end portion a transverse arm 9, at each end portion of which is a contact or electrode 10 of carbon or other suitable material. These 40 two contacts 10 are arranged to coöperate with two fixed contacts 11 which are carried by the terminal pieces 12 to which are connected the wires 13 of the circuit to be controlled by the relay.

14 designates a spring which is connected 45 at one end by an adjustable screw 15 to the base or support 16 of the instrument, and at its other end to the short arm of the lever 6. The screw 15 provides means for adjusting the tension of the spring 14, so that the lever 50 6 with its armature and contacts will be normally held or balanced in the open position shown in full lines in Fig. 2.

17 is an adjustable stop for the lever 6.

When the magnet coils 2 are energized by the local circuit 3, the armature 5 is attracted 55 by the poles 4, thereby actuating the lever 6 to bring the contacts 10 and 11 together. As soon as the circuit is broken in the coils 2, the spring 14 causes the contacts to immediately separate, and they are held separated 60 to such an extent as to prevent any possibility of current jumping from one to the other, or of arcs being maintained between them.

The advantages of my invention result 65 from the use of the combined armature and contact carrying lever having contacts on its long arm, together with the spring arranged to separate said contacts when the armature is released by the relay magnets, and to hold 70 such contacts in such widely separated position as to prevent the maintenance of an electric circuit between them.

Various changes may be made in the details of the construction and arrangement of 75 the various parts by those skilled in the art, without departing from my invention, since

What I claim is:—

In a relay device, a base, a magnet supported on a bracket secured to the base, a 80 lever having a short and a long arm, a shaft to which the lever is secured, brackets secured to the base having adjustable center bearings in which the lever shaft is journaled, an armature bar secured to the short arm of the lever, a contact bar having a contact at each end carried by the long arm of the lever, contact brackets each provided with a binding post and a contact secured to the base, the contacts on the brackets coöoperating 85 with the contacts upon the contact arm to complete a circuit between the binding posts when in contact with each other, a wire leading to each of the binding posts, wires leading to and from the magnet, an adjustable stop for the pivoted lever, and an adjustable tension spring to separate the contacts when the magnet is deënergized; substantially as described.

In testimony whereof, I have hereunto set 100 my hand.

CARL A. PALMGREN.
